UNITED STATES PATENT OFFICE.

FREDERICK C. STIMMEL, OF CHATTANOOGA, TENNESSEE, ASSIGNOR TO CASEY HEDGES CO., OF CHATTANOOGA, TENNESSEE, A CORPORATION.

WATER-TUBE BOILER.

Application filed April 15, 1920. Serial No. 374,129.

To all whom it may concern:

Be it known that I, FREDERICK C. STIMMEL, a citizen of the United States, and a resident of Chattanooga, in the county of Hamilton and State of Tennessee, have invented a new and Improved Water-Tube Boiler, of which the following is a full, clear, and exact description.

The object of the invention is to provide a new and improved water tube boiler more especially designed for high pressure steam service and capable of taking care of overload conditions.

Another object is to gradually heat the incoming feed water and thus reduce expansion strains on the water tubes to a minimum.

Another object is to utilize the fuel to the fullest advantage.

Another object is to insure a proper circulation of the water through the water tubes by maintaining a uniform tube area in the main boiler section and thus avoid reduced areas which impede circulation of the water.

With these and other objects in view, the invention consists of certain novel features of construction as hereinafter shown and described and then specifically pointed out in the claims.

A practical embodiment of the invention is represented in the accompanying drawings forming a part of this specification, in which the figure is an end view of the water tube boiler with the setting shown in cross section.

The water tube boiler in its general construction consists essentially of a main boiler section and a feed water section, of which the latter is in the rear of the main boiler section and both sections are arranged within a suitable setting 10. The main boiler section comprises a mud drum 15 connected by upwardly and forwardly extending water tubes 16 with an upper front drum 17 connected by rearwardly and slightly upwardly extending water tubes 18 with the rear upper drum 19, which latter is connected by vertical water tubes 20 with the mud drum 15.

The feed water section consists essentially of an upper entrance drum 25 connected by vertically disposed water tubes 26 with a lower feed water drum 27 arranged in the rear of the mud drum 15 connected by up-

right water tubes 28 with the upper rear drum 19 of the main boiler section. A feed water pipe 29 leads from a source of suitable water supply and discharges into the drum 25 of the feed water section. The upper rear drum 19 of the main boiler section is connected with the upper drum 25 of the feed water section by arched pipes 30 to conduct the steam from the drum 19 into the drum 25 from which the steam may be directly taken to a place of use, but is preferably conducted by a pipe 31 to a small drum 32 forming part of a superheater 33 arranged intermediate the upper portion of the water tubes 16 and the front portion of the water tubes 18. The drum 32 is connected by steam tubes 34 with a drum 35 from which the superheated steam is carried off to the place of use.

The upper drums 19 and 25 are supported on beams 40 forming part of a structural steel framework built in the setting 10, and the drum 17 is supported on a bracket 41 connected with the front upright 42 of the structural steel framework. By the arrangement described the upper drums 17, 19 and 25 are supported by the framework while the lower drums 15 and 27 are held in suspension and hence are free to expand.

The setting 10 is provided at the front lower portion with a fire box 50 into which the fuel is fed with a suitable stoker 51, and the fire box 50 is provided in the back with a fire wall 52 extending in front of the mud drum and reaching to the lowermost of the water tubes 16. From the top of the fire box 50 leads a continuous passage to the chimney connection 53 arranged on the rear wall 54 of the setting and this passage is formed by a number of baffles 60, 61, 62, 63, 64, 65, 66 and a wall 67 arranged intermediate the fire wall 52 and the back wall 54 and reaches to the bottom of the lower feed water drum 27. It will be noticed that by the arrangement described, the products of combustion arising from the burning fuel in the fire box 50 strike the water tubes 16 first and then pass upward and around the upper front drum 17 and rearward between the upper portion of the water tubes 16 to heat the superheated tubes 34, and then the rising products of combustion pass between the water tubes 18, then travel rearwardly over the baffle 63 to pass around the front portion of the rear upper drum 19, then downward be-

105

110

tween the tubes 20 to the water drum 15 and the lower feed water drum 27 to then pass up between the baffles 65 and 66 to heat the feed water tubes 28 and to then reach the rear of the drum 19 and the front lower portion of the drum 25 as well as the connecting steam tubes 30, and to then pass down between the baffle 66 and the rear wall 54 to heat the water tubes 26 and the rear portion 19 of the drum 27 and to finally pass through the chimney connection 53 into the chimney.

From the foregoing it will be seen that the feed water passing into the drum 25 and down the tubes 26 into the drum 27 and 15 from the latter up through the tubes 28 is gradually subjected to the lowest heat in the setting and hence the water tubes 26 and 28 are not subjected to undue expansion. It 20 will be noticed that the feed water is subjected to two passes of the products of combustion while passing down the water tubes 26 and up the water tubes 28, and hence the feed water discharges into the drum 19 practically at boiler temperature and by passing 25 down the water tubes 20 finally reaches the mud drum 15 thus mingling with the hot water in the main boiler. The water rising from the mud drum 15 through the tubes 16 is subjected to the highest heat in the 30 boiler. The water passing through the water tubes 16 into the front upper drum 17 passes from the latter by way of the water tubes 18 to the rear upper drum 19 in which the water is in more or less violent ebullition, and in order to prevent the steam in 35 this drum 19 from carrying along any water it is preferably conducted by the arched pipes 30 into the feed water drum 25. Any water is carried over by the steam into the feed water contained in the drum 25 while the steam passes from this drum by way of the pipe 31 to the superheater 33 to be superheated and then carried to the place of 40 use in a dry, highly heated state.

45 The drums 15 and 27 are provided with valved blow-off or draining pipes 70, 71 for periodically carrying off accumulated sediment. The setting is also provided with the usual cleaning holes 80 to permit convenient 50 periodical cleaning of the boiler of soot.

Having thus described my invention, I claim as new and desire to secure by Letters Patent:—

55 1. In a water tube boiler, a main boiler section and a feed water section, the main boiler section having a mud drum, a front upper drum, a rear upper drum in a higher plane than the front drum, a set of upwardly and forwardly inclined tubes connecting the mud drum with the front upper drum, a set of upwardly and rearwardly inclined tubes connecting the front and rear upper drums, a set of vertical tubes connecting the rear upper drum with the mud 60 drum, the feed water section having an up-

per receiving drum in rear of and in the same horizontal plane as the rear upper drum of the boiler section, a connection for steam only between the tops of the rear upper drum of the boiler section and the upper 70 receiving drum of the feed water section, a lower feed water drum in rear of the mud drum and disconnected therefrom, a set of vertical tubes connecting the upper receiving drum of the feed water section with the feed water drum of said section, a set of vertical tubes connecting the upper rear drum of the boiler section with the feed water drum, and a plurality of angularly arranged 75 baffle plates in the space bounded by the tubes connecting the drums of the boiler section, a baffle between the tubes of the upper drum and the mud and feed water drums, and a baffle in the tubes connecting the receiving drum with the feed water 80 drum.

2. In a water tube boiler, a main boiler section and a feed water section, the main boiler section having a mud drum, a front upper drum, a rear upper drum and sets of 90 water tubes connecting the said drums with each other, the said feed water section having an upper drum connected with a feed water supply and arranged in the rear of the said rear upper drum of the main boiler 95 section and having only a steam connection with said drum, a lower drum in the rear of the said mud drum and disconnected from said drum, a set of water tubes connecting the said upper and lower feed water drums with each other and a set of water tubes connecting the said lower feed water drum with the said rear upper drum of the main 100 boiler section, and a setting including a fire box, a continuous circuitous passage and a chimney connection in the lower part of its rear wall, the fire box extending under the set of tubes connecting the mud drum with the upper front drum of the main boiler section, the said continuous passage conducting the products of combustion arising from the burning fuel in the said fire box first to the set of tubes connecting the mud drum with the upper front drum, then to the latter, next to the set of tubes connecting the front and rear upper drums of the main 110 boiler section with each other, then to the rear upper main boiler drum, then down to the set of tubes connecting the upper rear drum of the main boiler section with the mud drum, then to the latter and the bottom drum of the feed water section, then up the set of tubes connecting the said bottom of the feed water section with the rear upper 115 drum of the main boiler section, then to the upper feed water drum and then down the set of tubes connecting the feed water drums with each other to the chimney connection. 120
